UNITED STATES PATENT OFFICE

JAMES BROPSON, OF CLEVELAND, OHIO, ASSIGNOR OF ONE-HALF TO JAMES J. BROPSON,
OF CLEVELAND, OHIO

FLASHING RING

Application filed June 19, 1928. Serial No. 286,690.

This invention relates to roof flashings and has particular reference to a novel and improved type of flashing such as commonly used on soil or vent pipes which project through the roof of a building.

The usual practice is to provide a suitable flashing ring to surround the pipe which projects through the roof, and then seal the joint between the ring and pipe by tamping 10 oakum or similar material therein, after which molten lead is applied to the joint. This practice involves considerable time and labor, as the joint must first be caulked to prevent the hot lead from passing through 15 the joint and then the lead must be melted and carefully poured in the space between the pipe and flashing ring.

The primary object of the present invention is to provide a roof flashing which shall 20 be formed with a lead collar securely attached to the flashing ring so that when installing the same, it shall be necessary merely to tamp the lead collar into engagement with the pipe to insure a water proof joint. 25 In this manner the steps of caulking with oakum and the application of molten metal to the joint are eliminated during the installation of the flashing ring.

Another object is to provide a roof flashing of the aforesaid character which shall have the usual lead plate that seats on the 30 surface of the roof, permanently attached thereto in a novel manner so that a water tight joint is formed without the application 35 of molten metal during the installation of the flashing ring.

A still further object is to provide a device 40 of the aforesaid character which shall be simple in construction, and inexpensive to manufacture, and which may be easily and quickly installed to provide a water tight joint.

With these and other objects in view, the invention may be stated to consist in the 45 various novel features of construction and arrangement or combination, all of which will be fully described hereinafter and pointed out in the appended claims.

In the drawings accompanying and forming part of this application, Fig. 1 is a top

plan view of a roof flashing constructed in accordance with my invention, but with the lead collar removed;

Fig. 2 is a vertical sectional view showing the lead collar in place, but prior to tamping; 55

Fig. 3 is a detail sectional view showing the collar tamped into sealing engagement with the pipe;

Fig. 4 is a top plan view of a modified form 60 of flashing;

Fig. 5 is a vertical sectional view through such modified form and showing the lead collar prior to tamping; and

Fig. 6 is a fragmentary vertical sectional view through a still further modified form 65 of flashing ring.

Describing the various parts by reference characters, and referring particularly to Figs. 1-3 inclusive, 1 denotes generally a 70 flashing sleeve which is preferably in the form of an iron casting. This sleeve is formed with a base 2 having lateral projections 3, for a purpose to be referred to hereinafter, and diametrically disposed lugs 4 that are adapted to receive bolts 5 or other 75 suitable fastening means to secure the flashing sleeve in position on the roof. A groove 6 is formed in the upper surface of the base 2 and receives therein the edges of a sheet lead plate 7 that overlies the projections 3 and 80 lugs 4 and forms a water tight joint between the base 2 and the roof. The edges of the lead, defining an elliptical aperture in the plate, are secured in the groove 6 by pouring molten lead 8 therein or by tamping a lead 85 ring in place therein. As shown in Fig. 2, the groove 6 is preferably undercut so that in cross section said groove is dovetail in shape, and thus the edges of the sheet lead are prevented from pulling out even if the lead 8 should become loose for any reason. 90

The upper annular portion 9 of the sleeve is formed with an inwardly directed shoulder 10 having a plurality of notches 11 95 formed therein. Suitable side walls 12 interconnect the base 2 with the upper portion 9 of the sleeve. The notched shoulder 10 serves as an interlock for a lead collar 13 which is preferably molded in position between the inner surface of said ring and the 100

outer surface of said pipe, and as shown in Fig. 2, this lead collar extends over and lies flat upon the upper edge of the cast iron sleeve and upwardly a considerable distance. 5 The inner surface of the collar is cylindrical and of a diameter somewhat greater than the pipe 14 that is adapted to extend therethrough, while the outer surface of said collar is tapered upwardly as indicated at 15.

10 In practice a unit structure, consisting of the cast iron sleeve with lead collar 13, molded in position and with the sheet lead plate 7 attached in the manner described above is manufactured and sold to the trade. This 15 type of flashing is particularly useful where it is necessary to position the flashing on the roof before the vent pipe 14 has been installed. An aperture 16 is cut in the roof at the desired location and the sleeve is bolted 20 to the roof over the aperture, the projections 3 serving to support the sleeve in case the aperture has been cut too large for the base ring to rest on the roof along its entire surface. The lead plate 7 is flattened on the roof 25 and the roofers may then proceed to lay the shingles or other roofing material over the lead plate. When the plumbing operations have reached a stage where the soil or vent pipe is to be installed, this pipe is inserted 30 through the flashing ring from the inside of the building, after which the upwardly projecting portion 15 of the lead collar is tamped into engagement with the pipe as shown in Fig. 3. In view of the interlock between the 35 lead collar and cast iron sleeve, this tamping operation may be easily carried out without loosening the seal between these two elements and at the same time a water tight joint is provided about the pipe. In this 40 manner, the use of molten metal and caulking with oakum is completely eliminated during the installation of the flashing, and hence considerable time and labor is saved.

45 In Figs. 4 and 5 I have illustrated a modified form of flashing and particularly in connection with the manner of attaching the lead plate 7^a to the base of the cast iron sleeve. In this instance the wall 12^a extends below the plane of the base 2^a, as indicated at 16, 50 and engages the roof to support the sleeve therein. Also the under side of the base 2^a is formed with an annular groove 6^a, which in cross section is dovetail in shape. The edges of the aperture in lead plate 7^a are deflected into this groove, and molten lead 8^a is applied to the groove as explained above in connection with Figs. 1-3. The shape of groove 6^a prevents the lead and edges of the plate from becoming disengaged from the 55 sleeve even though the lead 8^a should become loosened for any reason. By extending the wall 12^a below the plane of base 2^a it will be noted that the entire weight of the flashing is supported by the wall 12^a on the roof, hence 60 there is no danger of the base 2^a cutting

through the lead plate 7^a. The upper portion of the sleeve is identical with that described in connection with Figs. 1-3 inclusive and hence needs no further description. This type of flashing is useful where the soil pipe 70 has been positioned through the roof and the flashing is to be applied thereto before the roof has been laid. In this instance also, the lead collar 13^a and lead plate 7^a are affixed to the cast iron sleeve during the course of 75 manufacture thereof so that the steps of caulking with oakum and heating and pouring of molten metal are eliminated during the installation of the flashing.

80 In Fig. 6 I have illustrated a still further modification of flashing ring wherein 18 denotes a cast iron sleeve or ring having a slightly rounded exterior surface and an undercut inner surface. A lead plate 7^b extends over the upper edge of the ring and is 85 deflected over and against the undercut surface of the cast iron ring. A lead collar 13^b is then molded over the sheet lead plate and is formed with an upstanding portion 15^b. This type of flashing is useful where the angle of 90 the roof cannot be accommodated with the type of flashing previously described. The upstanding lead collar is caulked as previously explained in connection with Figs. 1-5 inclusive. The cast iron ring 18 is also provided with radially projecting lugs 19 which are adapted to engage the roof and support the 95 flashing where the aperture in the roof has been cut larger than the ring.

100 What I claim is:

1. A roof flashing comprising a ring adapted to seat upon the roof and surround a pipe projecting through said roof, and a soft metal collar permanently connected with said ring and adapted to fill the intervening space 105 between the inner surface of said ring and the outer surface of said pipe, said soft metal collar extending over and lying flat upon the upper edge of said ring, and being tapered upwardly therefrom, whereby said soft metal collar is adapted to be tamped into engagement with said pipe to form a weather tight joint between said ring and pipe.

110 2. A roof flashing comprising a rigid cast metal ring adapted to seat upon the roof and surround a pipe projecting through said roof, and a soft metal collar permanently connected with the interior surface of said ring, the metal of said collar being interlocked with the metal of said ring, said collar extending over and lying flat upon the upper edge of said ring and being tapered upwardly therefrom, whereby said soft metal collar is adapted to be tamped into engagement with said pipe to form a weather tight joint between said ring and pipe.

115 3. A roof flashing comprising a rigid cast metal ring adapted to seat upon the roof and surround a pipe projecting through said roof, a soft metal collar permanently connected 120

130

with the inner surface of said ring and extending over and lying flat upon the upper edge of said ring, and being tapered upwardly therefrom whereby said collar is adapted to be tamped into engagement with said pipe to form a weather tight joint between said ring and pipe, and a soft flexible metal plate permanently connected with said ring and adapted to engage the surface of the roof to form a weather tight joint between said roof and ring.

4. A roof flashing comprising a rigid cast iron ring adapted to seat upon the roof and surround a pipe projecting through said roof, and a lead collar and a lead plate each permanently connected to said cast iron ring, said collar being attached to the inner surface of said ring and extending over and lying flat upon the upper edge of said ring and being tapered upwardly therefrom whereby said collar is adapted to be tamped into engagement with said pipe to form a weather tight joint therewith, and said plate being adapted to form a weather tight joint between said roof and ring.

5. A roof flashing comprising a rigid cast metal ring adapted to seat upon the roof and surround a pipe projecting through said roof, said ring being formed with an inwardly extending shoulder having a plurality of notches therein, and a soft metal collar permanently connected with said ring, and filling the intervening space between the inner surface of said ring and the outer surface of said pipe, and seated on said shoulder and extending over and lying flat upon the upper edge of said ring, while being tapered thereabove, the metal of said collar being interlocked with the notches in said shoulder, the portion of said collar extending above said ring being adapted to be tamped into engagement with said pipe to form a weather-tight joint between said ring and pipe.

In testimony whereof I affix my signature.

45 JAMES BROPSON.
